SPRING LOADED SAFETY VALVE

James L. Corcoran, Bridgeport, Conn., assignor
to Manning, Maxwell & Moore, Incorporated,
New York, N. Y., a corporation of New Jersey

Application January 14, 1947, Serial No. 721,917

2 Claims. (Cl. 137—53)

1

This invention pertains to spring-loaded safety valves such as are customarily employed to release excessive pressure from a fluid pressure container such as a steam boiler or oil still.

Such a valve is illustrated, merely by way of example, in Patent No. 2,293,799, granted August 25, 1942, on an application filed in the name of Briscoe, and, as illustrated therein, comprises a hollow casing or body which houses a valve seat and a movable valve head or feather which has a lateral delivery passage. The movable valve head is loaded by means of a coiled compression spring arranged within a bonnet mounted on top of the casing proper. This bonnet is usually a casting and being a casting must be made heavy to insure the requisite strength. This heavy bonnet casting is of such an irregular shape that it is hard to handle during the machining operations, and hence it is difficult to finish it in such a manner as to insure a straight line thrust of the loading spring when the parts are assembled. The base flange of the bonnet casting is usually secured to the casing proper by means of six or more bolts, and the assembly of the bonnet with the casing thus involves the insertion of these bolts and the proper tightening of the nuts. Moreover, as the bonnet is of fixed dimensions, the exchange of one loading spring for another which is longer or shorter, as is sometimes desirable in order to adapt the valve for use with a different pressure range, involves expensive machining of the bonnet or its exchange for another.

It has heretofore been proposed to transmit the spring pressure to the casing simply by means of a pair of diametrically opposite tension rods instead of the usual cast bonnet, but as heretofore devised a pair of tension rods has not been found satisfactory because such rods offer but little resistance to force exerted in a direction transverse to the plane defined by the axis of the rods, and thus this arrangement, although simple and having many advantages, has not been widely adopted. Furthermore such an arrangement of the tension rods does not insure accuracy of alignment of the spring thrust.

One object of the present invention is therefore to provide a bonnet structure of the kind wherein the spring load is carried by a pair of tension rods but so devised as to provide the requisite stiffness transversely of the plane of the rod axes to prevent bending of the rods in response to the application of any usual force. More specifically as illustrated the spring load is transmitted to the casing by the use of two parallel diametrically spaced tension rods, but with pro-

2

vision for supporting said rods at points intermediate their lengths, thereby to support them in opposition to bending stresses.

A further object is to provide a safety valve 5 wherein the bonnet structure is simple, light in weight and stronger than the usual bonnet casting and which may be made more cheaply and which may be assembled more easily with the casing than the usual cast bonnet. A further object 10 is to provide a bonnet structure such that the spring load is carried by rods of a relatively high tensile strength as compared with cast rods and which may be made from standard bar stock. A further object is to provide a bonnet structure 15 wherein the bridge which supports the abutment for the upper end of the spring may be of standard rolled stock instead of a casting, thus decreasing weight while insuring adequate stiffness. A further object is to provide a valve so devised that the machining operation requisite to the attachment of the bonnet to the casing may all be carried out from the top of the casing, thus simplifying the procedure and insuring accuracy of alignment of the parts. Other and further objects 20 and advantages of the invention will be pointed out in the following more detailed description and by reference to the accompanying drawings 25 wherein

Fig. 1 is a vertical section through a spring-loaded safety valve embodying the invention, the section being in a plane perpendicular to the vertical plane of the axis of the delivery passage; and

Fig. 2 is a fragmentary horizontal section to smaller scale substantially on the line 2—2 of 35 Fig. 1 and showing the casing proper without other parts.

Referring to the drawings, the illustrated valve 40 comprises a body or casing proper 1 usually a casting or forging having a bottom flange 2 by means of which it is secured to a pressure container such as a boiler, superheater or the like, the flange 2 being united to the body by a neck portion 3 of smaller diameter than the body proper. A seat-supporting sleeve 4 of the general type disclosed in Patent No. 1,668,453, to 45 Graesser et al., granted May 1, 1928, is here shown as secured within the neck 3 of the valve body and in coaxial relation to the neck, this sleeve defining a vertical inlet passage 5 and having a 50 valve seat at its upper end.

The valve seat is located within a delivery chamber 6 in the casing body, this delivery chamber opening into a discharge passage 7 (Fig. 2) whose axis is substantially perpendicular to the 55 axis of the inlet passage 5.

A rigid annulus 10 is fixed to the top of the casing by bolts 11. This annulus 10 constitutes clamping means for securing the horizontal flange of a guide sleeve 12 to the casing body, this guide sleeve 12 having a vertical bore accurately aligned with the valve seat and which forms a guide for the cylindrical skirt portion 13 of the valve head. The valve head has an axial socket for the reception of the lower end of a valve-actuating spindle 15. The spindle extends up through the annulus 10 and through a steam deflecting shield 16. Above the shield 16 the spindle has a shoulder 17 which forms a support for a lower abutment disk 18 on which rests the lower end of a coiled compression spring 19. The upper end of the compression spring, by means of which the valve head is urged toward the valve seat, bears against an upper abutment disk 20, the latter resting against the lower end of an adjusting sleeve 21 surrounding the spindle and having screw-threaded engagement with a bore at the center of a transversely elongate bridge 22. This bridge is preferably of rolled bar stock and of sufficient thickness and rigidity so that it is not substantially deflected when subjected to the full load imposed by the spring 19. The valve spindle 15 extends up through the sleeve 21 and is provided at its upper end with an abutment collar which is engaged by the usual valve-lifting lever 23 by means of which the valve may manually be lifted from its seat.

As here illustrated the casing 1 is provided at diametrically opposite points with integral rigid outstanding lugs 24 and 25. These lugs are disposed above the plane of the bottom flange 2, lie substantially in the plane of the lower wall of the chamber 8, and have vertical bores therein whose axes are parallel and diametrically opposed, as respects the axis of the inlet passage 5, and in a plane preferably perpendicular to the vertical plane of the discharge passage 9. The bores in the lugs 24 and 25 receive the lower ends of tension rods 26 and 27. These rods preferably are standard bar stock turned to the shape here illustrated and are of steel of very high tensile strength. By the employment of the steel of high tensile strength it is possible to reduce the diameters of these bars and thus very substantially reduce the weight of the bonnet structure, as compared with the usual cast bonnet.

The rods 26 and 27 are provided near their lower ends with shoulders 30 and 31 which rest upon the upper ends of the lugs 24 and 25, respectively, and are screw threaded at their end portions for engagement with nuts 32 and 33, by means of which they are securely anchored to the lugs 24 and 25.

Near their upper ends the rods 26 and 27 are furnished with shoulders 34 and 35 which engage the under side of the bridge 22 bordering bores formed in the opposite end portions of the bridge. The rods extend up through these bores and their end portions are screw threaded for engagement with nuts 36 and 37, respectively, by means of which the rods are securely clamped to the bridge.

In accordance with the present invention, the casing 1 is provided with a second pair of diametrically opposed lugs 38 and 39 extending outwardly from its opposite sides and spaced directly above the lugs 24 and 25. These lugs 38 and 39 are situated above the plane of the valve seat substantially at the top of the valve casing and have vertical bores therein axially aligned with the bores of the lugs 24 and 25. The rods 26 and

27 are provided with cylindrical portions 41 and 42 of substantially larger diameter than the main body of the rods, these cylindrical portions being so located that they pass through and occupy the bores in the lugs 38 and 39 with a close sliding or drive fit.

In forming the bores in the lugs 38 and 39 the drilling or boring tool is advanced downwardly and through the lug 38, for example, and then 10 without withdrawal thereof further down through the corresponding lug 24, thus insuring accuracy of alignment of the bores in the lugs 38 and 24, the same accuracy of alignment being true of the 15 bores in the lugs 39 and 25. Thus, when the rods are passed through the bores of the lugs 38 and 39 and secured in the bores in the lugs 24 and 25, the rods are accurately parallel and held very 20 rigidly in this accurately parallel relation by the lugs 38 and 39 which, in effect, constitute bearing sleeves and which sustain the tension rods in opposition to bending force which might tend to throw them out of parallelism.

It may be noted that the two pairs of lugs 24-25 and 38-39 project but a short way from the body of the casing so that they are very rigid 25 and devoid of any tendency to bend in response to load even though they are not of very large dimensions. Likewise since the axes of the tension rods are quite close to the casing body there is 30 little tendency to distort the latter, even though the walls of the body be quite thin.

While, as here illustrated, the bores for the reception of the rods are formed in lugs projecting oppositely from the casing body, it is within the 35 scope of the invention to provide the casing body with continuous peripheral flanges in which these bores may be formed, such flanges, if employed, adding stiffness and rigidity to the casing body, which may be desirable under some conditions.

40 Likewise, although but two diametrically opposed rods are here illustrated, it is within the scope of the invention to provide more than one pair of such rods, and in the latter event the rods employed would obviously be disposed symmetrically with respect to the axis of the inlet passage and in such a manner as to avoid interference with the delivery passage.

Other and further modifications and rearrangements are to be regarded as falling within the 50 scope of the appended claims.

I claim:

1. A safety valve of the kind which comprises a hollow casing housing a valve seat and a movable valve head, and which has an inlet passage 55 coaxial with the seat and a discharge passage whose axis is substantially perpendicular to that of the inlet passage, a compression spring for loading the valve head and a bonnet structure including a transversely elongate a bridge which supports an abutment for the upper end of the spring, and a pair of diametrically opposite, parallel tension rods whose axes are in a plane perpendicular to the horizontal diametrical plane of the discharge passage, the casing having apertures for the lower ends of the rods disposed in a plane below the plane of the valve seat, means 60 securing the lower ends of the rods in the respective apertures, the bridge having apertures at its opposite end portions for the upper ends of the rods, and means securing the upper ends of the rods in said latter apertures, characterized in having rigid bearing sleeves which grip the rods intermediate their ends, thereby to oppose forces 65 tending to bend the rods, said bearing sleeves

being integral portions of the casing and located near the top of the latter.

2. A safety valve of the kind which comprises a hollow casing housing a valve seat and a movable valve head, and which has a compression spring for loading the valve head and a bonnet structure including a transversely elongate bridge adapted to support the upper end of the spring, and a pair of diametrically opposite, parallel tension rods, the upper ends of which are secured in the opposite ends of the bridge and the lower ends of which are secured in lugs formed integral with the casing in a plane below the valve seat, characterized in that the casing has other integral bearing lugs disposed in a plane above that of the valve seat, said latter lugs having vertically

elongate bearing openings axially aligned with the openings in the first mentioned lugs for receiving the lower ends of the rods, the apertures in the bearing lugs being of a diameter to receive the respective rods with a snug fit, thereby to brace the rods in opposition to bending forces.
